UNITED STATES PATENT OFFICE.

FREDERICK C. WEBER, OF NEW YORK, N. Y.

MONEY-HANDLING SYSTEM.

Application filed January 21, 1920. Serial No. 353,006.

To all whom it may concern:

Be it known that I, FREDERICK C. WEBER, a citizen of the United States, residing in the city, county, and State of New York, ⁵ have invented a new and useful Improvement in Money-Handling Systems, of which the following is a specification.

In banking institutions, the duties of the paying teller require that moneys paid out ¹⁰ shall be counted two or more times, in order to avoid error. The time required in handling such transactions and the accuracy of the count add to the inconvenience of the customers, who at times, must be marshalled ¹⁵ in long waiting lines at the teller's window. Another great desideratum is the added responsibility of the teller in making up large amounts in specified denominations to meet the requirements of the customers in making ²⁰ up payrolls. Change making devices for handling fractional currency and coins made up into rolls of specified amounts are provided for convenient handling, but so far as I am aware, no attempt has been ²⁵ made to provide means for handling bills with the same degree of facility.

It is the purpose of my invention to provide a means for the rapid handling of money of larger denomination, as well as ³⁰ a system of arrangement whereby ready access is instantly had not only to bills of any denomination, but in any desired amounts within reasonable limits.

In carrying out my invention, I make use ³⁵ of the several devices and structures set forth in the annexed specification and illustrated in the accompanying drawings, wherein—

Fig. 1 is a plan view of a teller's window ⁴⁰ and counter with a simple form of my invention fitted thereto.

Fig. 2 is an elevation of the same.

Fig. 3 is a side elevation of one of the drawer sections for holding the money containers, partly broken away to show the interior arrangement.

Fig. 4 is a vertical section of one of the drawer compartments.

Fig. 5 is a fragmentary perspective view ⁵⁰ of the tops of two adjacent drawers.

Fig. 6 is a vertical longitudinal section of a modified form of the invention.

Fig. 7 is a fragmentary plan of a part of the teller's counter, partly broken away to ⁵⁵ expose one of the drawers in plan.

Fig. 8 is a fragment of one of the bill containers, showing the method of its attachment to the feeding tape.

Fig. 9 is a side elevation of a series of such containers showing the same attached ⁶⁰ to the feeding tape.

Fig. 10 is a front view of a series of the containers showing their disposition within a drawer compartment.

Fig. 11 is a further modified form of the ⁶⁵ invention designed to handle containers of a different form and makeup.

Fig. 12 is a plan of a pair of drawer sections, one in full and the other with the hand operated feed rollers removed; also, ⁷⁰ the plan and disposition of a set of live feed rollers belonging to the adjoining section.

Figs. 13, 14, 15 and 16 show different forms ⁷⁵ of containers adapted for use in connection with the several forms of the invention.

Similar reference numerals refer to like parts throughout the specification and drawings.

Figs. 1 to 5, inclusive illustrate the simplest form of my invention. It consists of ⁸⁰ the teller's window 1, and counter 2, recessed at 3 to receive the tray 4, which latter contains the series of drawer sections 5, 5. These sections consist of open-sided drawers, divided into one, two or three compartments, according to their intended location ⁸⁵ within the tray. The drawers are symmetrically arranged on either side of the center line, as shown in Fig. 1, so as to leave the space 6 immediately back of the window 1, ⁹⁰ upon which the money containers are placed to be delivered to the customers. This arrangement also serves to locate the drawer sections at a safe distance from the window and out of convenient reach of a pilferer. ⁹⁵

Each drawer has a covered top 7, and forwardly curved partitions 8, at the upper edge of which the top 7 is slotted as at 9 and provided with the enlarged finger openings 10. Envelope containers 11, each having the correct amount of currency therein, as indicated upon its face, are placed within the several compartments, with the springs 12 pressing them forward against the front partitions 8. It will be noted that ¹⁰⁵ normally the upper end of the first container in any compartment does not register with the slot 9, but that such container must be bent forward to conform to the curve of the partition into such registry before it can be ¹¹⁰

removed from the compartment through the slot. This makes the extraction of containers from the window side of the counter all the more difficult, but does not interfere with ready removal of the containers from the opposite side; in fact, it is the easy and natural way to reach forward to a slot, run the finger over the tops of the exposed containers and upon reaching the first one, bend it forward to separate it from the others in order to get a hold upon it and then pull it out through the slot.

The forward part of the finger openings 10 is of such size as to expose a portion of 15 the upper end of the first container. Upon this exposed part, certain figures and letters are printed, to indicate, 1st, the amount of the contents of the container; 2nd, the series letter of the containers within that 20 compartment; 3rd, the denomination of the bills within the container; and 4th, the amount of the contents remaining within the compartment. For example, the exposed container in the left-hand compartment 25 shown in Fig. 5 indicates that each container has within it \$20 in \$2 bills; that it is now delivering the second or B-series, in other words, that the first lot or A-series has been paid out and that the compartment 30 is now delivering from the second filling; and finally the number 280 indicates that there is still a balance of \$280 within the compartment. This numbering system 35 serves as a continuing inventory of the contents of the compartment, since the next container would have the number 260 and the next 240 and so on. At the close of business, or at any other time, these exposed numbers may be gathered and jotted down, 40 and thus the contents of the entire tray may be readily ascertained without the necessity of counting. It is obvious that the containers must be correctly and consecutively arranged when placing them within the 45 compartments. This, however is previously done by other clerks and at times when the demands of the business permit, and upon whom the responsibility for accuracy of count and arrangement rests.

50 For convenience and ready accessibility of the various compartments within the tray, I prefer to arrange them as indicated in Fig. 1. Since the United States currency is based upon what is known as the 1, 2, 5- system, i. e., the bills are \$1, \$2, \$5; \$10, \$20, \$50; \$100, ( ), \$500; etc., the most convenient arrangement is to have the horizontal rows of compartments each 55 contain bills of the same denomination, with the amounts or numbers of such bills increasing in the same ratio in the vertical columns upon either side of the common center. Again, the 1's, 2's and 5's are 60 naturally placed upon the right hand side, 65 since the great bulk of banking transac-

tions cover amounts in which bills of these denominations form a part. The 10's, 20's and 50's are arranged in similar order upon the opposite side.

Since twenty to twenty-five bills within a container is a convenient limit in order not to unduly increase their bulk, I have indicated these numbers as the maximum, while the three compartments at the extreme ends of the tray may be set off to contain bills of still larger denomination as indicated. If desired, the designated contents of the containers may be printed upon the tops of the compartments, as shown in Fig. 1, but this may be omitted since the same information is conveyed by the printing upon the exposed ends of the containers as they are seen through the several finger holes 10.

When business is closed for the day the entire tray 4, with its contents, may be removed and replenished, for the next day's business, and thereafter stored in the bank vault over night for safekeeping. Should any of the compartments become exhausted during the day's business, the drawer containing that compartment will be removed and a full or reserve drawer with its contents substituted for it.

As above set forth, the handling of a 95 large banking business is greatly facilitated by the use of this system, even to such extent as to permit a single paying teller to do the work of two or three tellers working the old way. Again, large manufacturing and mercantile companies employing many hands, may make up their pay-rolls from trays previously prepared at the bank, and having their compartments filled with 100 containers of bills in certain predetermined and scheduled denomination. In this manner, the delay incident to the counting out of the money at the paying teller's window and the resulting inconvenience of a waiting line of customers is avoided.

The system as thus far described may be called "hand-operated", inasmuch as no operating mechanism is employed for delivering the containers, the teller merely having to select from the various compartments the amounts called for by the check demands of the customer. The central drawer marked "Coin", may contain coin money, either loose or in rolls, or it may be utilized 115 to house any one of the numerous change making devices now so commonly used in banks.

In Figs. 6 to 10 inclusive, I have illustrated a device for automatically delivering the containers to the teller upon pushing the proper buttons. In this form, the teller's counter or desk is provided with a series of delivery slots 12', as shown in Fig. 7. These slots extend vertically downward 125 in front of the live or driven rollers 13,

beneath the counter top, and staggered as to depth as clearly indicated in said figure. Drawers 14 are placed beneath the counter, having delivery slots 15 which register 5 with the slots 12. The sides of the drawers are open or cut away at 16, for the convenient insertion of the containers, which in this case are all attached to the ribbon of tape 17 and spaced apart. Springs 18 10 are located within the compartments to force the pack of containers forward against the separating partitions 19 or front 20 so that the first container may be passed upwardly through the delivery 15 slots 15 and 12'. Upon the tops of the drawers, the sliding frames 21, 22 are mounted; the pivoted frame 23 is mounted in the pocket 24 upon the front wall of the drawer. These frames are provided 20 respectively with the driven feed rollers 25, 26, 27, take-up rollers 28, 29 and 30, together with the idle rollers 31. Springs 32 are employed to hold the several frames with their feed rollers out of contact with the live feed rollers 13. Upon depressing the push buttons 33 respectively, these frames will carry their respective feed rollers into contact with the container within the slot 15 and force it against the live 25 roller 13, by which it will be projected through the slot 12 to a point within easy reach of the teller. Upon giving the container a slight pull it will be detached from the tape 17, which is wound upon the take up roller 28, 29, or 30 as the case may be. Even if not detached by the pull referred to, the container will be detached by being stripped from the tape 17 as the latter is forcibly drawn to the take-up roller. 30 The several take-up rollers have their trunnions mounted in slots 34 in their respective frames; springs 35 bear upon the yokes 36 to press the take-up rollers against the idle rollers 31, so as to ensure the consecutive 35 delivery of the containers and the proper disposition of the tape.

The staggering of the rollers 13, and the corresponding arrangement of the frames 22, 23, 24 permit the free sliding of the drawers beneath the counter without interference between the respective driving and driven feed rollers.

The tape 17 has the series of containers attached to it in any convenient manner, as 55 for example shown in Figs. 8, 9 and 10, by means of the stickers or slips 37, which are pasted partly to the container and partly to the tape, and spaced apart as shown. This will leave a fold of the tape 17, projecting below the ends of the containers when they are assembled in the compartments. In order that they may not bind 60 and interfold, I have provided the pair of ledgers or shelves 38 in the bottom of the drawer, so as to provide a channel 39 to

receive the folds of the tape, while the corners of the container ride upon the shelves 38.

In Figs. 11 and 12, I have shown a slightly different form of automatic delivery, to handle containers that are connected together in end to end relation and folded accordion fashion, for stacking into the compartments. The live rollers 40 are driven from an electric motor 41 which may be placed at the rear of the drawers and beneath the counter. The delivery slots 42 are shown as inclined forwardly toward the front of the counter, though this is not essential, since they may be vertically disposed as in Fig. 6. Since there is no tape to dispose of, no necessity arises for the use of take-up rollers and they together with the idle rollers of the form shown in Fig. 6 are omitted. The driven feed rollers 43 are mounted in the horizontally sliding frames 44, 45, and 46 which are guided in slots 47 in the edges of the upwardly extended partition walls 48. Springs 49 hold the frames in their forward position with their rollers out of contact with the live feed rollers 40, except when depressed by means of the push buttons 50, at the front ends of the drawers. The drawer delivery slots 51 are formed at the rear ends of the compartments by extending the rear walls 48 upwardly and upturning the adjacent portion of the drawer top 52. In the angle formed by the upturned drawer tops the retaining dogs 53 are located to bear upon the containers as they are drawn upwardly and prevent their slipping back into the compartments when the pressure of the feed rollers 43 is released.

The prepared containers are stacked into the compartments, with the initial container carried up into the delivery slot 51, with its upper end adjacent to the roller 43, and in position to be gripped between it and the live roller 40. The dogs 53 will hold the initial container in this position while the drawer is being placed in position, after which the delivery becomes automatic.

If desired, small gripping dogs 54 may be located at the rear side of the delivery slots 42, to facilitate the separation of the tandem containers as they are successively presented at the mouth of said slots. These dogs are pivoted between their ends and have cutting upper ends and gripping lower ends, so that when a container is pressed against the upper edge, in the act of tearing it off, the lower end is pressed against the rear side of the following container and holds it firmly while the exposed container is being severed.

The containers for the form of the device as shown in Fig. 1 are shown in Fig. 13. They are simple plain envelopes 55, having

printed upon its face or upon its flap 56, the contents, the series letter, the denomination of the contents and a number indicating the compartment balance. This same 5 form of container may be used with the form shown in Fig. 6, by pasting it to the tape 17 as hitherto described.

For the device as shown in Figs. 11 and 12, I have shown the containers 56' as formed 10 from a continuous strip of paper 57 as in Fig. 14, cross perforated at 58, cross cut at 59, and diagonally cut at 60. The strip is longitudinally scored to form the fold lines 61, 62. In making up a series, the selected 15 bills 63 are placed upon the side flap 64, and the triangular end flap 65 is folded over their ends. The side flap 64, with the bills thereon, is then folded over upon the body 66 of the container, and finally, the other 20 side flap 67 is folded over and pasted down upon the flap 64, or secured thereto in any other desired manner. Each section of the paper strip is treated in the same manner 25 until the entire series is made up, when they are folded up accordion fashion as shown in Fig. 16, ready to be placed in their proper drawer compartment.

In Fig. 15, I have shown a slight modification of the series container strip. In this 30 case, the strip 68 is cross cut at 69, and cross perforated at 71. Two flaps 72, 73 are cut out of the forward end of the body 74 of each container. The containers are made up by placing the selected bills upon the 35 body 74, with the flaps 72, 73 folded over their ends, and the side flaps 75, 76 folded over and pasted down or otherwise secured. The purpose of the several end flaps 65, 72, 73 is to form a closed end for the respective 40 containers. The cross perforations permit the ready severance of the successive containers as they are presented through the delivery slots.

It is to be understood that each of the 45 containers of a series will be exactly alike as to printed matter thereon, with the exception of the inventory number, which diminishes consecutively by an amount equal to the contents of each of that particular series 50 of containers.

The systematic order of arrangement of the compartments as shown in Fig. 1, is preserved in all of the other forms.

Inasmuch as the serial numbering of the 55 containers with numbers differing consecutively by an amount equal to the contents of the individual containers of the series, affords an automatic inventory of the remaining contents of a compartment when 60 such containers are withdrawn in reverse order, I regard this feature as of great importance, and desire to claim the same broadly. In order to make the record 65 complete, the containers may be directly numbered as well. Thus, each container

will have two serial numbers; one direct, indicating its order in the series or the number of containers already withdrawn; the other indirect or reverse indicating the contents remaining in the compartment.

I claim:

1. In a money handling system, the combination of a plurality of bill containers, means for storing said containers in systematic order as to amount and denomination of contents, and means for preventing the extraction of said containers from said storing means except in predetermined order.

2. In a money handling system, the combination of a plurality of currency containers, each having printed thereon indicia as to the amount and denomination of the contents thereof, means for storing said containers in systematic order relative to said indicia, and means for preventing the extraction of said containers from said storing means except in predetermined order.

3. In a money handling system, the combination of a plurality of money containers, a compartment in which said containers are stored in serial order, said compartment having a delivery slot therein for the extraction of said containers only in serial order.

4. In a money handling system, the combination of a drawer having a substantially closed compartment therein and having a delivery slot in the top thereof, a plurality of containers each containing the same amount of money in bills of the same denomination placed within said compartment, and means for permitting the successive delivery of said containers through said slot.

5. In a money handling system, the combination of a drawer having a plurality of compartments therein, a plurality of money containers arranged serially in sets and placed within said compartments in systematic order as to amounts and denomination of their contents, each compartment having a delivery slot therein for permitting the delivery of said containers therefrom in such serial order.

6. In a money handling system, the combination of a desk, a plurality of removable drawers therein, each drawer having one or more substantially closed compartments therein, a plurality of serially arranged money containers for each compartment, and systematically arranged throughout said compartments as to the amount and denomination of their respective contents, and each of said compartments having a delivery slot for permitting the extraction of said containers in serial order.

7. In a money handling system, the combination of a desk, a plurality of compartments within said desk each of said compartments having a delivery slot therein

- leading to the top of said desk or counter, a plurality of sets or series of money containers serially arranged within each of said compartments and systematically arranged throughout said compartments with reference to the amount and denomination of their contents, and means for permitting the extraction of said containers through said delivery slots in serial order only. 5
10. 8. In a money handling system, the combination of a plurality of money containers, means for storing said containers in systematic order as to amount and denomination of the contents thereof, and means for automatically delivering said containers from said storing means in predetermined order. 15
9. In a money handling system, the combination of a plurality of currency containers each having printed thereon indicia as to the amount and denomination of the contents thereof, means for storing said containers in systematic order relative to said indicia, and means for automatically delivering said containers from said storing means in predetermined order. 20
10. In a money handling system, the combination of a plurality of money containers, a compartment in which said containers are stored in serial order, a delivery slot for said compartment, and means for automatically delivering said containers from said compartment through said slot in serial order only. 25
35. 11. In a money handling system, the combination of a drawer having a substantially closed compartment therein and having a delivery slot in the top thereof, a plurality of containers each containing the same amount of money in bills of the same denomination placed within said compartment in serial order, and means for automatically withdrawing said containers from said compartments through said slots in such serial order only. 30
45. 12. In a money handling system, the combination of a drawer having a plurality of compartments therein, a plurality of money containers arranged serially in sets and placed within said compartments in systematic order as to amounts and denominations of their contents, a delivery slot for each compartment, and automatic means for drawing said containers successively from said compartments in serial order only. 40
55. 13. In a money handling system, the combination of a desk, a plurality of removable drawers therein, each drawer having one or more substantially closed compartments, a plurality of serially arranged money con-
- tainers for each compartment and systematically arranged throughout said compartments with reference to the amounts and denominations of their contents, a delivery slot for each compartment leading to the surface of said desk or counter, and means beneath said desk for automatically delivering said containers through said slots to the surface of said desk. 65
14. In a money handling system, the combination of a desk, a plurality of compartments within said desk or counter, each of said compartments having a delivery slot therein leading to the top of said desk, a plurality of sets or series of money containers serially arranged within each of said compartments and systematically arranged throughout said compartments with reference to the amounts and denominations of their contents, and means beneath said desk for automatically delivering said containers to the top thereof in serial order. 70
75. 15. The combination in a money handling system, of a plurality of money containers connected together in serial order, a compartment in which said containers are stored in such serial order, said compartment having a delivery slot therein for the extraction of said containers therefrom in reverse serial order. 80
85. 16. In a money handling system, the combination of a drawer having a plurality of compartments therein, a plurality of money containers connected together and arranged serially in sets and placed within said compartments in systematic order as to amounts and denomination of their contents, each compartment having a delivery slot therein for permitting the delivery of containers therefrom in reverse serial order. 90
95. 17. In a money handling system, the combination of a plurality of money containers, a compartment in which said containers are stored in serial order, a delivery slot for said compartment, and means for automatically delivering said containers from said compartment through said slot in reverse serial order. 100
105. 18. In a money handling system, the combination of a drawer having a substantially closed compartment therein and having a delivery slot in the top thereof, a plurality of containers each containing the same amount of money in bills of the same denomination placed within said compartment in serial order, and means for automatically withdrawing said containers from said compartment through said slot in reverse serial order. 110
115. FREDERICK C. WEBER.
